PARTITION STRUCTURE

John Page, Evanston, Ill.

Application April 26, 1934, Serial No. 722,473

23 Claims. (Cl. 72—46)

This invention relates to building constructions, and has reference more particularly to partition structures for use in buildings, together with their methods of erection.

5 In dividing rooms of buildings into smaller rooms, it is desirable to provide a partition construction which is as inexpensive as possible and at the same time provides sufficient rigidity to prevent flexing of partitions due to sudden 10 changes in air pressure, as upon the closing or opening of doors. It has been found that plaster board or fiber board, of a type well known to the art, when erected so as to form a self-supporting plaster base, can be used in a single 15 thickness as a core for a solid plaster partition which is independent of studs or other vertical structural members.

An object of this invention, therefore, is to provide a partition construction and a method 20 of erection which will be low in cost of erection.

Another object of the invention is to provide a partition structure of inexpensive nature which will have sufficient rigidity to withstand sudden applied forces such as changes in atmospheric 25 pressure; also to improve building constructions in other respects hereinafter specified and claimed.

Reference is to be had to the accompanying drawings forming a part of this specification, in 30 which

Figure 1 is a fragmentary side elevation of one embodiment of the self-supporting building board base or panel which forms the core of my partition construction. The panel is shown completely assembled and before the application of plaster thereto, the floor and ceiling being indicated in section;

Fig. 2 is a transverse sectional view through a partition during an intermediate stage of construction;

Fig. 3 is a transverse sectional view through the finished partition;

Fig. 4 is a sectional elevation showing a modified form of partition structure;

Fig. 5 is a sectional view through the partition structure taken on lines 5—5 of Fig. 4;

Fig. 6 is a perspective view of a section of a device adapted to serve as a base for supporting the partition structure;

Fig. 7 is a perspective view of a type of strap used in the device shown in Fig. 6;

Fig. 8 is a perspective view of a modified form of strap similar to that shown in Fig. 7;

Fig. 9 is a sectional view through a stiffening channel with board attaching clips in position;

Fig. 10 is a sectional view similar to Fig. 9, but showing an arrangement of clips for use about the edges of a partition;

Fig. 11 is a transverse sectional view through a modified form of stiffening channel and clip 5 arrangement;

Fig. 12 is an elevation through a further modified form of partition structure;

Fig. 13 is a sectional elevation through the partition structure shown in Fig. 12; 10

Fig. 14 is a sectional plan view through the partition shown in Fig. 12;

Fig. 15 is a sectional plan view through the partition structure shown in Fig. 12, showing an arrangement of electrical outlet boxes; 15

Fig. 16 is a sectional elevation showing a further modified form of partition structure;

Fig. 17 is a transverse sectional view through the partition structure shown in Fig. 16;

Fig. 18 is a sectional elevation through the 20 partition structure shown in Fig. 16;

Fig. 19 is a sectional plan view through a pair of intersecting partition structures of the type shown in Fig. 16;

Fig. 20 is a sectional plan view through two 25 intersecting partition structures of the type shown in Fig. 16;

Fig. 21 is a sectional plan view through a further modified form of partition structure;

Fig. 22 is a sectional elevation through the 30 partition structure shown in Fig. 21;

Fig. 23 is a sectional plan view through a reinforcing strip used in the partition structure shown in Fig. 21;

Fig. 24 is an elevation of the reinforcing strip 35 used in the partition structure shown in Fig. 21; and

Fig. 25 is a perspective view of a base clip used in my improved partition structures.

The invention in its simplest form is illustrated 40 in Figs. 1, 2, and 3, in which a plurality of building boards 30 are arranged in edge to edge, co-

planar relation in a vertical plane to form a base or panel for the reception of layers of plaster 31 and 32 and 31_a and 32_a on the faces thereof. 45

The building boards 30 may be of any of the materials well known to the art, such as gypsum board, with a gypsum core and paper cover sheet,

fiber board made of vegetable or mineral fibers, etc. The boards are arranged with their joints 50 staggered as illustrated in Fig. 1, and at the junction of the corners of two boards with the middle of the adjacent board, a clip 33 is provided, said

clip being arranged with outstanding fingers 34 forming opposed channels for engaging board 55

- edges and corners. Along the bottom of the partition, a plurality of clips 35 is provided, said clips 35 having outstanding fingers 36 which form a board-receiving channel along one face of the clip.
- 5 The ends 37 of the clip 35 are provided with suitable apertures 38 for receiving nails to attach the clip to the floor 39, said clips being also suitable for attachment to a ceiling 40 for supporting the upper edges of the partition-forming boards.
- 10 The boards 48 are preferably arranged in a vertical plane with the length or machine direction of the board vertical and arranged in tiers with horizontal joints staggered. The plaster base thus erected is sufficiently rigid to be self-supporting by reason of the fact that there is no continuous joint or plane of weakness extending perpendicular to the direction of principal stress. In a partition of the usual proportions of height and length it is well known that the most effective 15 method of stiffening the partition is to provide stiffness in a vertical direction. In erecting a plaster base without studs it is desirable to have the greatest stiffness in a vertical direction or between floor and ceiling.
- 20 The strength and stiffness of plaster boards and fiber boards are markedly higher when stressed parallel to the machine direction of the board than when stressed perpendicular to the machine direction. This is due to the fact that the fibers 25 in the paper on the plaster board and the fibers in fiber board are largely orientated in a direction parallel to the machine direction. Like any fibrous material, these boards are strongest parallel to the length of the fibers. Therefore, the 30 boards make the strongest and stiffest plaster base and partition when their fibers are parallel to the principal stresses in the partition. Also the resistance to bending when wet is markedly greater parallel to the fibers. The boards absorb 35 water from the scratch coats; then, due to the weight of the wet still-plastic plaster acting in a vertical direction, they have a tendency to buckle and sag out of a vertical plane. This tendency is best resisted when the machine direction of the 40 board is parallel to this stress.
- 45 Stiffness and rigidity is also enhanced by staggering the joints as I have done in my preferred form of partition.
- 50 After the layers of plaster 31, and 32, are applied to both faces of the board, the partition is very rigid and is not easily flexed by the sudden application of the weight of a person or by a sudden change in atmospheric pressure, such as that caused by opening and closing of doors.
- 55 However, in applying the first plaster layers 31 and 32, it may be desirable to use temporary stiffeners 42 and 42a which are secured to the plaster base as by nailing from the opposite side of the board 38 into the stiffener with nails 43. Vertical stiffeners 42 are applied to one side of the partition and horizontal stiffeners 42a to the opposite side.
- 60 These stiffeners may be 1" x 2" wood strips applied on edge. They need not extend in one piece the full height or width of the partition. Ends of the stiffeners should be lapped to give continuous stiffness. The function of the stiffeners is to hold the plaster base rigid against the pressure of the trowel and to prevent any warping or sagging of the plaster base due to the wetting action of the scratch coats 31 and 32 and subsequent pull of the plaster as it sets.
- 65 After the scratch coats 31 and 32 have set the stiffeners 42 and 42a are removed and the partition 70 is then sufficiently rigid to permit application of

the following layers of plaster 31a and 32a, known as the brown coats, without the use of further stiffening means. The white or finish coats 31b and 32b are applied to the coats 31a and 32a to complete the partition. These three coats, namely, the scratch coat, the brown coat, and the finish coat, bring the wall thickness to 1½" or 2", so as to provide a rigid monolithic partition of durable construction. 5

In order to further increase the rigidity of the 10 partition, which may be desired under certain conditions, stiffening channels 52, as illustrated in Fig. 5, may be interposed between the board edges at intervals of every, say, three rows of board, said channels extending vertically and 15 preferably being somewhat shorter than necessary to reach at top and bottom to the ceiling 40 and floor 39, respectively. The channels 52 are preferably of steel and have outstanding flanges 53 along each edge which extend parallel to the 20 plane of the partition, the web of said channel extending at right angles to said plane.

In order to secure the boards 50 to the channels 52, I provide a plurality of clips 54 which have outstanding pairs of fingers 55 for forming a 25 channel to receive the edges of the building boards 50. The clips 54 rest in abutting relation against the webs of channels 52 and are held thereagainst by means of straps 56, which are preferably U-shaped in cross section and have outstanding 30 legs 57 which are adapted to embrace the channel flanges 53. The straps 56 are depressed as shown in Fig. 7 to contact with the web of the channels on the side of the channel carrying the flanges 53, or said straps 56 may be straight as shown in Fig. 8 to contact with the web of the channels on the 35 face of the channel opposite the flanges 53.

It is often desirable to embed electrical conduits 58 in the layer of plaster 51 and for this reason some of the building boards 59 are offset 40 from the plane of the remainder of the boards to give room for said conduits 58. In order to position the clips 54 in offset relation relative to the clips on the opposite side of the channel 52, I provide notches 60 along each edge of the strap 45 56, said notches 60 engaging about the edges of fingers 55 for positioning purposes. The clip ends 61 are clipped off along one side to form shoulders 62 which lie adjacent one of the flanges 53 to permit the offset positioning of said clip 54. 50 The strap attaching means 56 is preferred since it permits the use of standard stiffener channels 52 which can be purchased locally in any locality where the partition is to be constructed. However, in certain cases it may be found desirable 55 to attach the clips 54 to the channel 52 by means of rivets 63, by spot-welding, or the like, in which case the clips 54 would be assembled on the channels 52 and shipped to the job in assembled form.

The use of stiffener channels 52 avoids the use 60 of the vertical temporary stiffeners 42. The horizontal stiffeners 42a may be used but in this case will extend only between the stiffener channels 52. After the first layer of plaster 51 and 51a has been applied and set, the horizontal stiffeners 65 42a are removed and a second layer of plaster 64 and 64a is applied (see Fig. 5), in order to provide a finished partition, as previously described. Channels 65 may be run along the bottom of the partition to receive the bottom 70 edges of the board, clips 35 being used along the ceiling 40 to receive the top edges of the boards forming in part the partition. Grounds or nailing strips 67 may be provided at intervals along the bottom of the partition for use in the attach- 75

ment of base boards 68. These grounds 67 preferably extend vertically to insure the application of plaster to the extreme bottom of the partition, but, if desired, a ground strip may be applied horizontally (Fig. 13) for the same purpose.

The building boards 50 are preferably provided with perforations 70 which extend completely through the same. These perforations are preferably spaced 4" on centers and spaced 2" from all of the edges of the board. The perforations are preferably 3/4" in diameter so as to permit a key of plaster 71 to pass completely through the boards when the first layer of plaster 45 is applied and form a head 72 (Fig. 14) on the far side of the board. The exact dimensions and spacing of the perforations 70 may be varied somewhat, but the optimum condition for proper plaster application is more specifically described in the patent to C. K. Roos, No. 1,938,354. When the second coat of plaster 73 is applied to the far side of the boards, it attaches itself to the heads 72 and thus the two layers of plaster 45 and 73 become united through the boards to form a monolithic construction. This perforated type of board is especially desirable when used on this particular type of partition because the heads 72 not only attach themselves to the layer of plaster 73, but aid materially in enabling the plasterer to properly trowel the plaster layer 73 on the far side of the partition. Similar action takes place at the joints between the board where a key of plaster passes through and is engaged by the layer of plaster applied to the far side of the board. In Fig. 14 the brown coats are shown at 46 and 46a applied, respectively, to scratch coats 45 and 73, and the finish or white coats are shown at 47 and 47a applied to coats 46 and 46a, respectively.

The perforations 70 in the board 50 are an important part of the partition where a high fire-resistance is desired. In a partition in which both faces of plaster are not tied together the plaster face exposed to a fire will, after being calcined, fall away from the partition and allow the heat of the fire to strike through to the core and back plaster face. If the core or plaster base is a combustible material, such as fiber board, the core will burn and add fuel to fire already present. In the case of a non-combustible plaster base such as plaster board, the heat will strike through the core, calcine the back plaster face, and cause it to crumble. When both plaster faces are tied together, as by the perforations 70 in my preferred type of partition, the plaster face exposed to the fire is held in place by virtue of the keys extending into the plaster on the opposite side of the partition. The exposed plaster face remains intact and shields the plaster base from the flame and acts as an insulator retarding the passage of heat into the core and plaster face. Other advantages of the perforations 70 will appear. By means of the perforations, stiffeners 42 and 42, and ground block 67 can be easily located for attachment by the mechanic on the opposite side of the partition. Perforations 70 also facilitate the attachment of corner bead 90 by wire 91 and attachment of clips 95 by wire 97.

The form of partition shown in Figs. 16 to 20 differs from those previously described in that metal stiffener channels 76 are located completely outside the plane of boards 77. In this form of partition one layer of plaster 78 on one side of the board 77 is thinner than the layer of plaster 79 on the other face of the board so as to give space for the passage of electrical conduits 80 up through the thick layer of plaster 79. Special

clips 81 are secured, as by spot-welding, to outstanding fingers 82 of board connecting clips 83, the clips 81 being bent around the channel 76 at the time of erection to hold said channel in position adjacent the face of the boards 77. In this form of partition, horizontal ground strips 84 may be attached to the boards 77, the space below said ground strips 84 being also filled with plaster 85.

Figs. 19 and 20 illustrate methods of attaching one partition to another at the corner of a room. In Fig. 19, a clip 86 is attached, as by spot-welding, to fingers 87 of a clip 88, so that fingers 89 on clip 86 extend at right angles to the fingers 87 forming channels for the reception of the boards 77 at the corner of the room. A corner bead 90 of any standard design, may be attached to the boards 77 by wiring 91. In the intersecting partition shown in Fig. 20, a channel 93 extends along the face of boards 94 forming a longitudinal partition. Clips 95 consist of fingers 98 extending from base 96 and are secured to board 94 by means of a wire 97, said clips 95 with the outstanding fingers 98 forming a channel for the reception of boards 99 which extend at right angles to the boards 94.

In the form of partition shown in Figs. 21 to 24, I utilize what I term a "screed stiffener strip" 100 which is preferably of metal. It extends vertically and in length is somewhat less than the height of the partition to be constructed, the edges of said strip being reversely bent to form flanges 101. Boards 102 extend in both directions from the stiffener strip 100, being held in position by means of clips 103 having fingers 104 extending through openings 105 formed in the strip 100. Since each of the clips 103 has a number of fingers 104, a plurality of said openings 105 are provided in one group located adjacent the ends of the boards. A plurality of perforations 106 pass through the screed strip 100 and the flanges 101 to give proper keying of the plaster through the edges of said strip, thus preventing cracking of the plaster adjacent said strip. The edges of the strip 100 serve as screeds to insure a plane surface on the brown coat of plaster and thus aid the plasterer in constructing the partitions. The strip 100 has considerable longitudinal stiffness transversely of its plane so as to impart the necessary stiffness to the boards 102 in applying the layers of plaster.

In partitions, such as that shown in Figs. 12 and 15, an electrical outlet box 109 is connected to the conduit 58 and is embedded in the plaster 47. The boards 50 are slotted below the box 109 to give clearance for the conduit 58. A U-shaped strap 110 is connected to the box 109 by bolts 111, the ends 112 of said strap lying in abutting relation against the boards 50. Wires 113 pass through one of the perforations 70 and connect to a strap 114 so as to attach said box 109 to boards 50 prior to the application of the plaster 47. A similar arrangement is used in the partition shown in Fig. 21 except that a strap 115 has ends 116 which are wired to the near side of boards 102. In the form of partition shown in Fig. 17, the conduit 80 has an offset 117 to pass along the boards outside of the plane thereof.

While I have described more or less precisely the details of construction, I do not wish to be understood as limiting myself thereto, as I contemplate changes in form, the proportionate parts, and the substitution of equivalents, as circumstances may suggest or render expedient.

without departing from the spirit of my invention.

Having thus described my invention, I claim as new and desire to secure by Letters Patent:—

- 5 1. The method of erecting a partition, which comprises arranging plaster boards edge to edge in a substantially vertical plane with joints broken, connecting said boards together, providing one side of said boards with stiffening members, applying a plaster coating to the other side of said boards, and then applying a coating of plaster to the first mentioned side of said boards.
- 10 2. The method of erecting a partition, which comprises arranging plaster boards edge to edge in a substantially vertical plane with joints broken, connecting said boards together during erection by means of metallic clips, providing one side of said boards with temporary stiffening members, applying a plaster coating to the other side of said boards, removing said stiffeners, and then applying a coating of plaster to the first mentioned side of said boards.
- 15 3. The method of erecting a partition which comprises arranging building boards in vertical tiers, with horizontal joints broken, fixing the ends of said boards to substantially the central portion of the edges of adjacent boards so as to form a self-supporting substantially vertical assembly, the applying of temporary stiffeners on one or both sides of the plaster base, and then applying a scratch coat of plaster to both sides of said base, removing the temporary stiffeners after the scratch coat has set, and applying finishing coats to said scratch coats to 20 form a rigid partition.
- 25 4. The method of erecting a partition which comprises arranging building boards in horizontal courses and breaking joints, the applying of temporary stiffeners on one or both sides of the plaster base, and then applying a scratch coat of plaster to both sides of said base, removing the temporary stiffeners after the scratch coat has set, and applying finishing coats to said scratch coats to 25 form a rigid partition.
- 30 5. The method of erecting a partition which comprises arranging perforated building boards in horizontal courses and breaking joints, the applying of temporary stiffeners on one or both sides of the plaster base, and then applying a scratch coat of plaster to both sides of said base, removing the temporary stiffeners after the scratch coat has set, and applying finishing coats to said scratch coats to 30 form a rigid partition.
- 35 6. A partition construction, comprising a core of rectangular, perforated building boards arranged edge to edge with the horizontal joints broken and the major axes of said boards extending vertically, attaching members connecting the edges of said boards to maintain said boards in coplanar relation during erection, and a layer of plaster applied to each face of said boards and connecting through the perforations thereof to provide a monolithic, rigid partition.
- 40 7. A partition construction, comprising a core of rectangular, perforated building boards arranged edge to edge with the joints broken and the major axes of said boards extending horizontally, attaching members connecting the edges of said boards, stiffeners associated with said boards to maintain said boards in coplanar relation, and a layer of plaster applied to each face of said boards and connecting through the perforations thereof to provide a monolithic, rigid partition.
- 45 8. A partition construction, comprising a core

of building boards arranged edge to edge with the joints broken, some of said boards being in a plane different from that of other boards, attaching members connecting the edges of said boards, a conduit extending along said first mentioned boards, and a layer of plaster applied to each face of said boards and covering said conduit to provide a monolithic, rigid partition. 5

9. A partition construction, comprising a core of building boards arranged edge to edge with the joints broken, stiffener metallic channels extending vertically between some of said board joints, some of said boards between said channels being offset and lying in a plane different from that of the other boards, attaching members connecting said boards and channels, a conduit extending along said offset boards, an electrical outlet box secured to said offset boards and connected to said conduit, and a layer of plaster applied to each face of said boards and 10 covering said conduit to provide a monolithic, rigid partition. 15

10. In a partition structure, a metallic channel arranged with the web thereof extending at right angles to the plane of the partition, metallic clips secured to opposite sides of said web and having outstanding fingers forming channels for the reception of the edges of building boards, the clips on one side of said web being located near the center line of said web, the 20 clips on the opposite side of said web being located a substantial distance from the center line of said web so as to offset some of said boards from the plane of the remaining boards, a conduit extending along said offset boards, and a layer of plaster applied to each face of said boards so as to form a rigid, monolithic partition. 35

11. In a partition structure, a metallic channel arranged with the web thereof extending at right angles to the plane of the partition, metallic clips secured to opposite sides of said web and having outstanding fingers forming channels for the reception of the edges of building boards, metallic straps embracing said channel and securing said 40 clips to said channel, and means in said straps permitting positioning of clips substantially in the center of said web or offset to either side of the center. 45

12. A partition structure, comprising a core of building boards arranged edge to edge with horizontal joints broken, metallic strips of substantially the same width as the thickness of the partition disposed in some of the vertical joints, each of said strips having perforations at intervals along its length substantially in the center of the width of the strip to allow the tongues of clips used in attaching adjacent building boards to pass through said metallic strip, and a layer of plaster applied to each face of said boards to 50 form a rigid construction. 55

13. In a partition structure, a plurality of building boards arranged edge to edge with joints broken, metallic clips connecting the edges of said boards, a metallic stiffener strip secured to one 60 face of said boards, and a layer of plaster covering each face of said boards and embedding said strip to form a rigid, monolithic partition. 65

14. In a partition structure, a plurality of building boards arranged edge to edge with joints broken, clips connecting the edges of said boards, base board nailing strips attached to one or both faces of said boards near the bottom of said partition, said nailing strips extending substantially vertically, a layer of plaster applied to each 70 75

- face of said boards, and a base board secured to said nailing strips.
15. A building construction, comprising angularly disposed wall panels, the edge of one of said panels being adjacent a face of a second panel, stiffener member adjacent the other face of said second panel, attaching means engaging the edge of said one panel, and means connecting said stiffener and attaching means and binding said 10 panels into relatively fixed relationship.
16. A thin monolithic fire resistant wall structure comprising perforated plaster boards in closely adjacent substantially coplanar relation, means connecting the vertical edges together in a manner to provide a self-supporting panel and to transfer lateral stress from the ends of the boards to intermediate the ends of adjacent boards, a plaster coating each side of said plaster boards and extending through said perforations 20 to form an integral plaster unit enclosing said boards, the plaster perforations being arranged to retard calcination of the plaster therein considerably beyond that of the surface plaster when the structure is subjected to continued high temperatures, and to retain the surface plaster between perforations after the surface plaster has 25 calcined.
17. The method of erecting a thin fire resistant partition, which comprises arranging perforated building boards in a substantially vertical plane, with horizontal joints broken, connecting the adjacent vertical edges of said boards together in a manner to transfer lateral stress from the end of one board to the vertical side of an adjacent 30 board, providing one side of said boards with stiffening members, applying a cementitious coating to one side of said boards with sufficient pressure to fill the perforations and to extend beyond the opposite surface, then applying a coating to the first mentioned side of said boards to form an integral cementitious covering.
18. A thin wall construction comprising a core of relatively thin building boards arranged edge to edge in vertical tiers with the horizontal joints broken, and relatively light attaching members connecting the vertical edges of said boards adjacent their ends and intermediate their ends to provide a transfer of lateral stress from the joint of two abutting boards to the side of an adjacent 45 board and remote from the end thereof, and a layer of plaster applied to each face of said core to provide a monolithic, rigid partition.
19. A thin fire resistant wall structure comprising a substantially rigid core formed of perforated plaster board units assembled in substantially coplanar self-supporting relation, means connecting said boards together in horizontal staggered relation whereby the lines of greatest resistance to lateral stress are in a vertical plane, a thin plaster coating covering each side of said core and completely filling said perforations to provide plaster bonds therein and to provide a monolithic structure when said plaster is set, said lines of greatest resistance and said 50 perforations and plaster bonds therein combining to prevent sagging or distortion of said wall while the plaster is setting and to provide effective fire resistant characteristics after setting.
20. A relatively very thin, fire-resistant monolithic wall structure comprising perforated plaster boards in adjacent edge to edge relation and in vertical tiers with horizontal joints broken, means connecting the vertical edges together in a manner to provide a self-supporting panel and to transfer lateral stress from the ends of the boards to a point intermediate the ends of an adjacent board, a thin coating of building plaster applied to each side of the plaster boards and 55 completely filling said perforations to form an integral unit with said boards, said perforations being of sufficient size and arrangement to distribute lateral stresses in a manner to materially reduce the tendency of the plaster to crack at the joints of the boards, and to retard calcination of the plaster bonds therein considerably beyond that of the surface plaster when either side is subjected to continued high temperature and to retain the surface plaster intact after the surface plaster has calcined.
21. A thin monolithic self-supporting fire resistant wall structure comprising a self-supporting core formed of perforated plaster board units in parallel coplanar tiers, means connecting the 25 edges of the units of adjacent tiers together in staggered relation whereby the lines of greatest resistance to lateral stress are parallel with said tiers, and plaster completely enclosing said core and filling said perforations.
22. A thin monolithic fire resistant wall structure comprising a core formed of fabric covered perforated plaster board units in coplanar relation, means attaching the edges of said boards together to form a self-supporting thin core, said 30 boards having comparatively large widely spaced perforations, a thin plaster coating on each surface of said core to form a thin wall and filling said perforations to form bonds between said coatings of sufficient size to materially resist calcination, the size and spacing of said perforations being related to enable the bonds to retain between adjacent perforations a comparatively large area of the plaster coating calcined by heat on one side of the wall whereby the fabric after 35 carbonizing is retained intact to form a layer of insulation and whereby the plaster and fabric on the opposite side are held intact.
23. A thin monolithic fire resistant wall structure comprising a core formed of perforated wall 50 board units in coplanar relation, said boards having easily carbonized surfaces, means attaching the edges of said boards together to form a self-supporting thin core, said boards having comparatively large widely spaced perforations, a 55 thin plaster coating on each surface of said core to form a thin wall and filling said perforations to form bonds between said coatings of sufficient size to materially resist calcination, the size and spacing of said perforations being related to enable the bonds to retain between adjacent perforations a comparatively large area of the plaster coating calcined by heat on one side of the wall whereby the surface after carbonizing is retained intact to form a layer of insulation and whereby 60 the plaster and surface on the opposite side is held intact.
